UNITED STATES PATENT OFFICE.

FRANK J. CREQUE, OF CUYAHOGA FALLS, OHIO.

DESIGN FOR A TOY BALLOON.

52,129.

Specification for Design.

Patented July 2, 1918.

Application filed December 18, 1916. Serial No. 137,733. Term of patent 14 years.

To all whom it may concern:

Be it known that I, FRANK J. CREQUE, a citizen of the United States, residing at Cuyahoga Falls, in the county of Summit and State of Ohio, have invented a new, original, and ornamental Design for Toy Balloons, of which the following is a specification, reference being had to the accompanying drawing, forming part thereof.

The figure is a perspective view of a toy balloon showing my design.

According to my design the surface of

the balloon is mottled by providing the same with intersecting lines, forming a mottled surface having an ornamental effect in colors.

I claim:

The ornamental design for a toy balloon, as shown and described.

FRANK J. CREQUE.
